William L. Fudge, Minneapolis, Minn., assignor to
Larsen's Manufacturing Company, Minneapolis, Minn.

Continuation of design applications Ser. No. 18,375, July
24, 1969, and Ser. No. 18,383, July 24, 1969. This
application Dec. 15, 1969, Ser. No. 20,711

Term of patent 14 years

Int. Cl. D29—01

U.S. Cl. D16—2

FIG. 1 is a view in perspective of a fire extinguisher cabinet, showing the top, front and one side of my new design;

FIG. 2 is a view in perspective showing the bottom, front and the side opposite that shown in FIG. 1;

FIG. 3 is a view in perspective showing the bottom, front and one side of a modified embodiment of the cabinet illustrated in FIGS. 1 and 2;

FIG. 4 is a side elevational view of the cabinet of FIG. 3 showing the side opposite that seen in FIG. 3;

FIG. 5 is a view in bottom plan of the cabinet of FIG. 3; and

FIG. 6 is a view in top plan of the cabinet of FIG. 3. The undisclosed rear portions of the cabinet are substantially plane and unornamented.

This application is a continuation of design applications Ser. Nos. 18,375 and 18,383, both filed July 24, 1969 and now abandoned.

I claim:

The ornamental design for a fire extinguisher cabinet, substantially as shown and described.
